UNITED STATES PATENT OFFICE

LOUIS A. HAVENS, JR., OF QUEENS VILLAGE, NEW YORK

AMMONIA-GAS DETECTOR

Application filed October 3, 1928. Serial No. 309,975.

The present invention relates to improvements in circuit makers and closers and has reference more particularly to a device for association with a refrigerating plant wherein ammonia is employed as the refrigerant.

One of the important objects of the present invention is to provide a means for closing an electric circuit to actuate an alarm or cut off the flow of the gas when a leak occurs in the pipe line thus providing a safety device for association with an ammonia operated refrigerating plant.

A further object is to provide an ammonia gas detector that will at all times be positive and efficient as well as automatic in its operation, the device being further simple in construction, inexpensive, strong and durable and further well adapted to the purposes for which it is designed.

Other objects and advantages will become apparent during the course of the following description.

In the accompanying drawing, forming a part of this specification, and in which like numerals indicate like parts throughout the same:

Figure 1 is a sectional view through the ammonia gas collecting hood showing the circuit maker and breaker constituting the present invention arranged therein,

Figure 2 is a top plan view of the device, the hood being shown in dotted lines,

Figure 3 is a vertical sectional view through the device,

Figure 4 is a sectional view taken approximately on the line 4-4 of Figure 3 looking downwardly illustrating the vertically swinging liquid receptacle in top plan,

Figure 5 is a top plan view of the reservoir, the cover therefor being removed,

Figure 6 is a detail perspective view of the liquid container or receptacle per se,

Figure 7 is a detail showing the manner in which the fine wire mesh screen is associated with the frame of the liquid container, and

Figure 8 is a sectional view taken approximately on the line 8-8 of Figure 1 illustrating one of the contacts.

In the drawings wherein for the purpose of illustration is shown the preferred embodiment

of my invention, the numeral 1 designates a hood in which the ammonia or other gas used in conjunction with a refrigerating apparatus that accidentally escapes when a leak occurs in the gas line is collected for actuating the circuit maker and breaker embodying the present invention.

The top of the hood is provided with a suitable opening 2 through which projects the upper portion of a substantially rectangular shaped open top reservoir 3 that is adapted to contain a reserve supply of water or other aqueous solution.

A removable cover 4 is provided for the open top reservoir. The present invention includes the provision of a base 5 located within the hood and extending upwardly from the rear end of the base is the standard 6 that supports at its upper end portion the reservoir 3. A pair of forwardly extending brackets 7 and 8 respectively are secured at their rear ends to the respective side edges of the vertical standards 6 at a point above the base 5 and a rod 9 extends transversely through the forward ends of the spaced brackets in the manner as clearly suggested in Figure 4.

A substantially rectangular shaped frame 10 is formed in its sides adjacent the rear end thereof with registering openings 11 to accommodate the transverse rod 9 whereby said frame is pivotally supported adjacent its rear end between the forwardly extending brackets in the manner as also clearly illustrated in Figure 4.

A cross bar 12 extends between the sides of the frame at a point forwardly of the registering openings 11 and secured over the sides of the forward end portion of the frame 10 and over the forward end and the cross bar 12 is a fine wire mesh screen 13, the central portion of which is dished whereby to provide what I term as a receptacle for the liquid or aqueous solution.

The foraminous material is of such a nature as to prevent the water or aqueous solution passing therethrough as long as there is nothing to come in contact with the water that would alter its surface tension.

This receptacle or container is denoted 102

generally by the reference character 14, and is provided with an overflow opening 15. A weight 16 is attached to the rear end of the frame 10.

5 For the purpose of preventing the downward swinging movement of the receptacle when the same is filled with the liquid or aqueous solution, I provide the pivoted latch 17, that is attached to one side of the frame 10 forwardly of the pivotal connection and the free end of this latch engages with a pin 18 that projects laterally from the adjacent bracket 7 as shown very clearly in Figure 1.

15 A vertically disposed tube 19 is arranged within the reservoir 3 adjacent the front side thereof and the lower end of this tube extends downwardly through the bottom of the reservoir for disposition directly above the rear portion of the liquid container or receptacle 14 as shown in Figures 1 and 3.

20 It will be observed upon referring to Figure 3 that the upper end of the tube 19 terminates at a point below the upper edge of the reservoir and at a point above the water level in 25 said reservoir.

30 A wick 20 of relatively long length is submerged within the liquid within the reservoir or the major portion thereof, the outer end of the wick extending downwardly through the tube 19. The purpose of this wick is to apply the liquid to the container 14 to replace that which is lost by reason of evaporation.

35 The circuit maker and breaker associated with the present invention comprises a block 21 that is secured on the outer face of an upwardly disposed extension 22 formed on the bracket 7 of the forward end thereof and as is clearly shown in Figure 8, the block 21 is insulated with respect to the extension 22.

40 A pair of spaced contacts 23 and 24 are arranged within suitable sockets provided in the top portion of the block 21 and as is clearly illustrated in Figure 8, each of the sockets provided for the aforesaid contacts is 45 lined with insulation denoted by the reference character 25.

45 A terminal 26 extends through the bottom of each socket 27 and an expansible coil spring 28 is arranged in each socket for disposition 50 between the heads of the terminal and the lower end of the respective contacts for normally urging the spring contacts upwardly in their respective sockets so that the upper ends of these contacts normally project beyond the upper surface of the block 21. The 55 terminals 26 are also insulated with respect to the block 21 and the lower ends of these terminals provide binding posts to which are attached the wires 29 that are connected to an 60 appropriate alarm or signal to a source of electrical supply, not shown.

65 The circuit to such signal is normally open and for the purpose of closing this circuit to effect the actuation of the signal or alarm, there is provided in conjunction with the

present invention, a contact bridging plate 30 that projects laterally from the side of the frame 10 and this plate is insulated from the frame as suggested in Figure 6.

70 The plate is disposed directly above the contacts 23 and 24 as suggested very clearly in Figure 1 and the manner in which this bridging plate cooperates with the aforementioned spaced contacts will be presently described.

75 While I have mentioned the use of the device as being adapted to operate an alarm or signal, it may be equally as well adapted for use in actuating the valve mechanism in the pipe lines that supply the ammonia or other refrigerating gas to the refrigerating apparatus by employing any well known valve actuating mechanism that is controlled by the closing of an electric circuit.

80 The operation of my improved ammonia gas detector may be briefly stated as follows.

85 Water or other aqueous solution is placed in the container 14 and as long as nothing comes in contact with the water that would cause the alteration of surface tension or density, the water cannot leak through the foraminous screen 13. Thus the weighted receptacle is held in the horizontal position keeping the plate 30 maintained out of engagement with the spaced contacts 23 and 24 thus keeping the circuit to the signal or valve actuating mechanism open.

90 However when the ammonia or other gas that is collected in the hood 1, from leakage in the refrigerating system, comes in contact with the liquid in the receptacle or container 14, and said liquid absorbs the gas to the extent that the surface tension of the liquid in the receptacle is lowered, the liquid in the receptacle will pass through the screen.

95 The release of the weight of the liquid will allow the weight 16 to swing the pivoted frame 10 downwardly in a rearward direction whereupon the plate 30 will bridge the contacts 23 and 24 thus closing the circuit to the signal or valve actuating mechanism.

100 The reservoir 3 provides a means for replenishing the liquid in the receptacle 14 that is lost by reason of evaporation and the liquid is conducted from the reservoir to the receptacle through the medium of the wick 20.

105 The drain or overflow opening 15 will compensate for the fast feeding of the liquid to the container. An aqueous solution of the proper specific gravity is employed when the device is used where temperatures are low, to prevent the liquid from freezing.

110 It will thus be seen from the foregoing description, that I have provided an ammonia leak detector for use in refrigeration plants that employ ammonia as the refrigerant that will automatically indicate when 115

a leak occurs in the pipe that supplies the refrigerant to the apparatus and in this manner said device will enable repairs to be made immediately and at the same time preventing an undue waste of the ammonia.

5 The simplicity in which my device is constructed enables the parts to be readily and easily assembled or disassembled and furthermore the detector will at all times be 10 positive and efficient in carrying out the purposes for which it is designed.

While I have shown the preferred embodiment of my invention, it is to be understood that various changes in the size, shape 15 and arrangement of parts may be resorted to without departing from the spirit of the invention and the scope of the appended claims.

Having thus described my invention, what 20 I claim as new is:

1. A gas detecting apparatus comprising in combination, a gas collecting hood, a standard arranged within the hood, a vertically swinging liquid container having a foraminous body, a circuit closer structure operatively associated with the pivoted container and the support and normally held in an inoperative position by the weight of the liquid in the container, said circuit closer structure 25 being disposed in an operative position when the gas collected in the hood comes in contact with the liquid in the container to lower the surface tension thereof and to cause the liquid to flow downwardly through the foraminous body of the container.

2. A gas detecting apparatus comprising in combination, a gas collecting hood, a standard arranged within the hood, a vertically swinging liquid container having a foraminous body, a circuit closer structure operatively associated with the pivoted container and the support and normally held in an inoperative position by the weight of the liquid in the container, said circuit closer structure 40 being disposed in an operative position when the gas collected in the hood comes in contact with the liquid in the container to lower the surface tension thereof and to cause the liquid to flow downwardly through the foraminous body of the container, and means for effecting the swinging movement of the pivoted container to dispose the closer structure in an operative position when the container becomes emptied.

5. A gas detecting apparatus comprising in combination, a gas collecting hood, a standard arranged within the hood, a vertically swinging liquid container having a foraminous body, a circuit closer structure operatively associated with the pivoted container and the support and normally held in an inoperative position by the weight of the liquid in the container, said circuit closer structure 50 being disposed in an operative position when the gas collected in the hood comes

in contact with the liquid in the container to lower the surface tension thereof and to cause the liquid to flow downwardly through the foraminous body of the container, and means for effecting the swinging movement of the pivoted container to dispose the closer structure in an operative position when the container becomes emptied, and a reservoir arranged on a support above the container for replenishing the liquid lost by evaporation.

4. A gravitationally movable control device for containing water, having a screen bottom adapted to prevent the passage of water through its interstices as long as the water is unaffected by anything that would alter the surface tension thereof and also adapted when the surface tension of the water is lessened to allow the water to pass through its said interstices.

5. A gas detecting apparatus comprising in combination, a support, a foraminous liquid container pivoted to the support, a circuit closer structure mounted on the support and cooperatively associated with the liquid container, said circuit closer normally held in inoperative position by the weight of the liquid in the interstices of the container and in the operative position when the interstices are free of liquid, a liquid reservoir mounted on the support, a conduit connected with the reservoir for supplying liquid to the container, and said support adapted to be disposed in proximity to gas conductors and receptacles in a refrigerating system for the purpose of permitting gas leakage to contact with the liquid held in the interstices of the container to decrease the surface tension of the liquid and cause said liquid to free itself from the container.

6. A gas detecting apparatus comprising in combination, a support, a foraminous gravitationally movable liquid container connected with the support, a circuit closer structure mounted on the support and cooperatively associated with the liquid container, said circuit closer normally held in inoperative position by the weight of the liquid in the interstices of the container and in the operative position when the interstices are free of liquid, a liquid reservoir mounted on the support, a conduit connected with the reservoir for supplying liquid to the container, and said support adapted to be disposed in proximity to gas conductors and receptacles for the purpose of permitting gas leakage to contact with the liquid held in the interstices of the container to decrease the surface tension of the liquid and cause said liquid to free itself from the container.

7. In a circuit closer, a support, a pair of electrical conducting terminals connected with the support, a gravitationally movable switch arm connected with the support, said arm having a foraminous layer of material thereon to prevent liquid under normal con-

ditions from passing therethrough and means connected with the arm for bridging said terminals when the layer is freed of liquid by contacting with a gas that causes a diminished surface tension in the liquid.

5 In testimony whereof I affix my signature.
